Des. 218,376
Patented Aug. 11, 1970

218,376

LUGGAGE CASE

Clair A. Samhammer, Orange, Calif., assignor to Samsonite Corporation, Denver, Colo., a corporation of Colorado

Original design application May 22, 1967, Ser. No. 7,201. Divided and this application Oct. 28, 1968, Ser. No. 14,206

Term of patent 14 years

Int. Cl. D3—01

U.S. Cl. D87—5

FIG. 1

FIG. 2

Des. 218,376

PAGE 2

FIG. 3

FIG. 4

FIG. 5

FIG. 6

FIG. 1 is a three-quarter side perspective view of a luggage case embodying my new design;

FIG. 2 is an end elevation of the luggage case of FIG. 1 but taken from the end opposite to that shown in FIG. 1;

FIG. 3 is a bottom plan view of the luggage case of FIG. 1;

FIG. 4 is a bottom plan view similar to FIG. 3, but showing a variation in the appearance of the feet or glides on the bottom of the luggage case;

FIG. 5 is a three-quarter side perspective view of the luggage case of FIG. 4;

FIG. 6 is an end elevation of the luggage case of FIG. 4.

This application is a division of my copending application Ser. No. D. 7,201, filed May 22, 1967.

I claim:

The ornamental design for a luggage case, as shown and described.
